UNITED STATES PATENT OFFICE.

LAWRENCE H. MORSE, OF CLEVELAND, OHIO, ASSIGNOR TO THE AMERICAN MULTIGRAPH COMPANY, OF CLEVELAND, OHIO, A CORPORATION OF OHIO.

PAPER DETECTOR FOR PRINTING MACHINES.

Application filed August 10, 1925. Serial No. 49,253.

This invention relates to mechanism associated with the paper feeding means of a printing machine for preventing the co-action of the printing members when the 5 paper fails to feed. The object of the invention is to provide a mechanism for this purpose which shall be simple in construction and efficient in operation. The paper detector of the present application is well 10 adapted for use in connection with the paper feeding mechanism of an addressing machine as shown and claimed in my prior application No. 757,352, filed December 22, 1924, wherein there is a rotary drum adapted 15 to coact with a platen to cause address plates fed between them to print on paper fed with the drum, a series of belts lying in engagement with a portion of the periphery of the drum furnishing means for feeding 20 the paper to the impression line.

The present invention provides a detecting device which is adapted to coact with the drum in the general region where the belts act against the drum, and thus such 25 detector engages a sheet of paper after it has been gripped by the belts and drum. Such sheet of paper covers a recess in the drum into which the detector would otherwise pass and thus prevents the detector 30 from operating its throw-out mechanism only when a sheet is being fed with the rotation of the drum. The detector has a roller bearing lightly against the paper so as not to mar it, and is controlled in its 35 position by the presence or absence of the sheet. The action of the detector is to cause the drum to be moved to idle position whenever the detector moves into the recess. This will all be explained more fully hereinafter in connection with the drawings.

In the drawings, Fig. 1 is a side elevation of a rotary paper feeding mechanism to which my detector is applied; Fig. 2 is a plan of such paper feeding mechanism; 45 Fig. 3 is a vertical section through the paper feeding drum and its cooperating parts; Fig. 4 is an end view of the driving gearing and paper controlling cam of the machine looking from the opposite direction 50 to Fig. 3; Fig. 5 is a vertical transverse section on a larger scale through the axes of the paper drum and platen; Fig. 6 is a perspective of a portion of the paper drum and the coacting detector arm and roller; Figs. 55 7 and 8 are diagrammatic elevations illus-

trating the action of the detector mechanism.

As shown, the frame of the machine comprises a suitable base portion 10 having a horizontal bed 11, an upright standard 12 at one end carrying a driving gearing, etc., and two standards 13 and 14 at the other end supporting the drum and the members which carry the belts. The main driving shaft, indicated at 20, is mounted in the standards 12 and 13, and directly beneath this, is a platen shaft 21 mounted in the base portion of the frame. The paper feeding drum 30 surrounds the shaft 20 and is driven by it and this drum coacts with the platen 40 which is mounted on the platen shaft. 60 The driving connection is shown as comprising a Oldhan coupling 25 between the shaft and one end of the drum. 70

Any suitable means may be employed for 75 rotating the shaft 20. I have shown by way of illustration a hand crank 22. Likewise, any suitable means may be employed for moving the platen with the same peripheral speed as the drum. My prior application referred to shows one mechanism for moving 80 the platen forwardly with the drum and thereafter swinging it back to idle position. In the present drawings, to simplify the illustration, I have shown the platen as rotary, being rigidly mounted on the shaft 21, 85 which is geared with the shaft 22 by the meshing gears 23 and 24.

The drum 30 which surrounds the driving 90 shaft 20 is rotatably mounted on an eccentric sleeve 50, which sleeve is internally journaled on the shaft 20 and externally in the standard 13. By turning the sleeve, the approach of the drum to the platen is varied. The paper detector mechanism hereinafter 95 described controls such turning and causes the drum to remain clear of the platen whenever the paper is absent.

The drum 30 is provided on its exterior with a yielding segmental impression surface 32 adapted to coact with the platen. 100 The drum carries a pair of elastic rings 33 and 34 beyond this impression surface and an intermediate arcuate elastic ring 35 extending about the drum substantially into engagement with the edges of the impression 105 surface.

Three belts 60 coact with the three rings 33, 34 and 35 (preferably soft rubber) on the paper drum. These belts are endless and lie side by side; in their lowermost region they 110

loop around the roller 61 on a stationary axis. The rearmost portion of each belt loops around an individual roller 62 spring-pressed rearwardly by a spring 63 acting on a lever 64 carrying the roller. At their forward and upper ends, the belts pass around a roller 66 carried by a movable yoke 67. The yoke 67 is pivotally mounted on a shaft 70 carried by the frame members. Rigid on this shaft is a rearwardly extending arm 72, to the rear end of which is connected an upwardly drawing spring 73. A forward extension of this arm is adjustably secured to the yoke by a screw engaging an ear 68 (Fig. 2) on the yoke. The tendency accordingly, is for the forward end of the yoke 67 to move downwardly carrying with it the roller 66 and the three belts, whenever the shaft 70 is free to turn.

At the far end of the shaft 70 is secured an arm 80 carrying a roller 81 coacting with a cam 82 on the gear 23. This cam is adjustably positioned by screws 85 locking it on the gear. When the cam acts to rock the roller 81 upwardly as shown in Fig. 4, this swings the yoke 67 upwardly carrying the rollers 66 with it, thus leaving a gap between the belts and rollers 90. These rollers 90 are sectional rollers projecting through openings in a paper table 91.

Between the sectional rollers are stop fingers 92 formed on the rearward ends of arms 93 carried by a rock shaft 94. When the roller 66 is elevated, as in Fig. 3, by the cam 82, space is thereby provided under which the operator feeds the paper until it engages the stops 92. Then when the cam 82 clears the roller 81, the yoke 67 swings downwardly under the influence of the spring 73, bringing the belts 60 into coaction with the rollers 90; at the same time, a screw 75 on an arm 74 rigid on the shaft 70 engages a rock arm (not shown) on the shaft 94, and rocks the stop fingers downwardly to idle position, so that the paper is gripped between the belts and the rollers 90 and fed rearwardly. In such feeding, the paper lies between the belts and the rubber rings 33, 34 and 35 until it comes between the soft segment 32 and the platen where the printing is effected, after which, the sheet may be discharged through the ejection chute 98, (Fig. 3).

The detector mechanism of this invention comprises a hard ring 100 mounted on the drum 30 and having an arcuate notch 101 with which cooperates a roll 105 on a rock arm 106 secured to a rock shaft 107. On this rock shaft is an arm 110 moving with the arm 106 and connected by a link 111 with an arm 112 shown as loosely depending from the shaft 70. Keyed on the shaft 20 is a cam 120 which coacts with a roller 121 on a rock plate 122 rigidly secured to a rock shaft 123. This rock plate has a portion extending over the shaft 20 and is provided

with a shoulder 125 adapted to engage the lower end of the arm 112. A spring 126 tends to pull the plate upwardly, and it may move upwardly or not according to whether its shoulder clears the arm 112 as shown in Fig. 7 or engages it as shown in Fig. 8.

The rock shaft 123 to which the cam plate 122 is rigidly secured, extends beyond the frame standard 13 and carries a rock arm 130 which is connected by a link 131 with an arm 132 adapted to turn the eccentric sleeve 50. As shown in Fig. 5, this arm 132 is loose on a short shaft 135 pinned to the eccentric sleeve 50, but the arm is adjustably connected by a screw 136 to an arm 137 rigid on this short shaft. The screw 136 passes through a slot in the arm 137, so that the position of the arm 132 relatively to the eccentric sleeve 50 may be adjustable, although in operation that arm is rigid with the sleeve.

From the description given, it will be seen that each rotation of the drive shaft 20 gives a rotation to the cam 120 which rocks downwardly the plate 122, thus rocking downwardly the arm 130 and turning the eccentric sleeve. This turning is in a direction to move the drum to idle position out of possible coaction with the platen. The decreasing portion of the cam, however, allows the spring 126 to rock the arm 122 to turn the eccentric sleeve in the direction to lower the drum into active position.

The cam 120 which is rigid on the main shaft 20 acts to lower the plate 122 and hold its shoulder 125 beneath the arm 112 before the notch 101 of the detector ring comes opposite the detector roller 105. Accordingly, when such notch comes opposite the roller, the shoulder 125 on the plate is below and free from the arm 112. Now if at this time, paper be absent, the roller 105 will swing into the notch under the influence of a coil spring 140 acting on the shaft 107 (Figs. 2 and 5) and this will carry the lower end of the arm 112 into the path of the shoulder 125 so that when the portion of the cam of greatest radius clears the roller 121, the plate 122 remains locked by the arm 112 as shown in Fig. 8, and thus the drum is retained in idle position with reference to the supporting platen 40, so that as the printing member is passed between the platen and drum there is no smudging of the impression surface on the drum.

If however, paper were present when the notch 101 passed the roll 105, that roll would be retained in its rearmost position as shown in Fig. 7, because the paper would prevent the roller passing into the notch 101, and this retained position of the roll will hold the arm 112 in idle position shown in Fig. 7, so that this arm 112 will not interfere with the action of the plate 122, and the plate roller 121 accordingly moves up

wardly when allowed to do so by a cam surface of decreasing radius. This rocks the eccentric to turn the drum to active position.

5 It will be seen that Fig. 7 indicates the normal operation wherein, on each rotation, the cam 120 first turns the eccentric to carry the drum to idle position and turns it to restore the drum to active position. Fig. 8, 10 on the other hand, indicates the abnormal condition where the paper is absent and the drum is blocked against the return to active position after the cam has moved to idle position.

15 To adjust the position of the depending arm 112, I have shown the arm 106 as pinned to this shaft 107, while the arm 110 is loose on this shaft and is connected therewith by means of a block 145 tight on the 20 shaft and connected with the arm 110 by a spring 146 and a set screw 147 screwed through the block and bearing against the arm.

25 As will be seen from Fig. 8, the notch 101 comes behind the detector roller at a time when the cam 120 is holding the shoulder 125 a slight distance below the path of the extreme lower end of the arm 112. Accordingly, there is no stress on that arm at the 30 time of its movement, and a very light spring 140 will be sufficient to insure the roller moving into the notch when the paper is absent. On the other hand, this light spring allows the roller to lie gently against 35 the paper and so does not mar it when the paper covers the notch 101.

It will be seen that my detector mechanism, while simple in construction, is effective in controlling the impression coaction. 40 Inasmuch as it acts after the paper has been gripped by the belts and drum, there is no opportunity for a faulty operation, such as might result if the detection were made before the paper was actually gripped.

45 Having thus described my invention, I claim:—

1. The combination of a rotary drum, means for holding paper thereon, said paper being adapted to overlie a recess in the 50 drum, a detector adapted to bear against the face of the paper when overlying the recess or move into the recess when paper is absent, a platen adapted to coact with the drum, and means controlled by said detector for preventing coaction of the drum and platen.

2. The combination of a rotary drum, means for holding paper thereon, said paper being adapted to overlie a recess on the 60 drum, a detector adapted to bear against the outer face of the paper when overlying the recess or move into the recess when paper is absent, a platen, mechanism for periodically separating and returning the drum and platen, and means controlled by said de-

tector for maintaining the drum and platen separated.

3. The combination of a rotary drum having a recess therein, means for holding paper on the drum over the recess, a detector 70 positioned to engage the paper directly over the recess during the rotation of the drum, a platen adapted to coact with the drum, an eccentric mounting for one of such coacting members, and mechanism for turning such mounting controlled by the detector.

4. The combination of a paper feeding drum having an impression surface, a belt coacting with the drum and adapted to hold paper against said drum, the drum having 80 a recess therein which such paper overlies, a detector adapted to engage the outer surface of the paper opposite the recess and thus have its position controlled by the presence or absence of paper, and means for retaining the impression surface active or idle according to the position of the detector.

5. The combination of a paper feeding drum having an impression surface, an eccentric mounting for the drum whereby its 90 axes may be shifted, endless belts coacting with the drum and adapted to hold paper against said drum, notwithstanding shifting of the drum axis, said drum having a recess which such paper overlies, a detector 95 adapted to engage the outer surface of the paper opposite the recess and thus have its position controlled by the presence or absence of paper, and means under the control of the detector for turning the eccentric 100 mounting.

6. The combination of a rotary drum having an impression surface and having elastic rings, belts bearing against such rings to hold paper on the drum, said drum having a notch adapted to be covered by the paper, a detector adapted to bear against the outer face of the paper over the notch, an eccentric on which the drum is mounted, means for turning the eccentric to bring the 110 drum into active position, and mechanism controlled by the detector when it enters the notch adapted to prevent such turning of the eccentric.

7. The combination with two coacting 115 members comprising a rotary paper feeding drum and a platen adapted to coact therewith, of mechanism whereby said members may be separated or brought together, a cam for operating said mechanism, the 120 drum having a notch therein adapted to be covered by the paper, a detector adapted to bear against the paper opposite the notch, and mechanism operated by the detector for preventing the operation of the cam-operated mechanism in the direction to cause coaction of the drum and platen.

8. The combination of a rotary paper feeding drum, a platen adapted to coact therewith, an eccentric mounting for one of 130

- said members whereby the members may be separated or brought together, a cam and mechanism operated thereby for turning the eccentric, the drum having a notch adapted 5 to be covered by the paper, a detector adapted to bear against the paper opposite the notch, and mechanism operated by the detector for preventing the operation of the mechanism operated by the cam.
10. The combination of a rotary paper feeding drum, an eccentric sleeve on which the same is mounted, a cam and mechanism operated thereby adapted to periodically turn the eccentric to present the drum to 15 active position and to withdraw it therefrom, a notch on the drum which the paper may overlie, a detector adapted to bear against the paper opposite the notch, and mechanism adapted to be moved by the detector into the path of the cam-operated mechanism.
10. The combination of a pair of coacting members adapted to have rolling contact, an eccentric sleeve on which one of the members 25 is mounted, a cam, mechanism operated by the cam for turning the sleeve, means coacting with one of said members and carrying paper with it, said member having a notch which the paper normally covers, a detector coacting with the paper opposite the notch, and an abutment adapted to be moved by the detector into the path of the mechanism operated by the cam.
11. The combination of a rotary shaft, an eccentric sleeve mounted thereon, a drum mounted on the sleeve and coupled for rotation to the shaft, mechanism for turning the eccentric sleeve, a notch on the drum, a detector adapted to coact with the notch 35 and mechanism controlled by the detector for preventing the operation of the turning mechanism.
12. The combination of a rotary shaft, an eccentric sleeve mounted thereon, a drum mounted on the sleeve and coupled for rotation with the shaft, a cam rotated by the shaft mechanism, mechanism whereby the cam turns the eccentric sleeve, a notch on the drum, a detector adapted to coact with the notch, and mechanism controlled by the detector for preventing the cam-operated mechanism from seating the drum.
13. The combination of a rotary driving shaft, an eccentric sleeve loosely mounted thereon, a drum loosely mounted on the eccentric sleeve, a shiftable coupling connecting the drum with the shaft, a cam on the shaft, a lever coacting with the cam and connected with the sleeve whereby the cam 45 turns the sleeve, a notch on the drum, a pivoted detector arm having a roller adapted to bear against the paper directly oppo-

site the notch, an abutment adapted to block the movement of the cam-operated lever, and a connection between said abutment 65 and detector arm.

14. The combination of a rotary driving shaft, an eccentric sleeve loose thereon, a drum loose on the sleeve, a coupling connecting the drum with the shaft, a pair of 70 elastic rings on the drum, endless belts coacting with said rings whereby the drum and belts may feed paper about the drum, a notch in the periphery of the drum adapted to be covered by the paper so fed, a detector adapted to bear against the paper in a position which will register with the notch, a periodically operating mechanism to turn the eccentric first in one direction and then the other, and means operated 75 by the detector when it enters the notch to prevent the operation of said mechanism in the direction to move the drum to active position.

15. The combination of a paper feeding 85 drum rotatably mounted on an eccentric adapted to be turned, elastic rings on the drum, an impression surface on the drum between the rings, a platen adapted to coact with the impression surface, a hard ring 90 on the drum adjacent to one of the elastic rings and carrying a notch, a shiftable roller adapted to track on said hard ring, said roller being in position to enter the notch unless the same is covered by the paper, a 95 cam rotated by the shaft, mechanism operated by the cam for turning the eccentric, an abutment adapted to block the movement of said mechanism, and a connection between said abutment and the detector 100 roller.

16. The combination of a rotary shaft, an eccentric sleeve loose thereon, a paper feeding drum loose on the sleeve, a shiftable coupling connecting the drum and shaft, 105 elastic rings on the drum, an impression surface on the drum between the rings, a platen adapted to coact with the impression surface, a ring on the drum adjacent to one of the elastic rings and carrying an arcuate 110 notch, a pivoted arm having a roller in position to enter the notch unless the same is covered by the paper, a cam rotated by the shaft, a lever operated by the cam, connecting mechanism between the lever and the eccentric, whereby the lever may turn the eccentric, a pivoted arm adapted to block the movement of said lever or clear it, and a connection between said arm and the detector roller.

In testimony whereof, I hereunto affix my signature:

LAWRENCE H. MORSE.
